The ornamental design for a fused electric power plug, as shown and described.

DESCRIPTION

FIG. 1 is a top plan view of a fused electric power plug showing my new design;

FIG. 2 is a left end elevational view thereof;

FIG. 3 is a right end elevational view thereof; FIG. 4 is a front elevational view thereof, the rear elevational view being a mirror image;

FIG. 5 is a bottom plan view thereof; and,

FIG. 6 is a front upper left perspective view thereof.

FIG. 1

FIG. 2

FIG. 3

FIG. 4

FIG. 5

FIG. 6
